CLAIM

The ornamental design for a “putting cup,” as shown and described.

DESCRIPTION

FIG. 1 is a side elevational view of a putting cup showing my new design, the opposite side being a mirror image thereof;

FIG. 2 is a front elevational view;

FIG. 3 is a rear elevational view;

FIG. 4 is a top plan view;

FIG. 5 is a top perspective view;

FIG. 6 is a top plan view of a second embodiment of the putting cup as disclosed in FIG. 1; and,

FIG. 7 is a top perspective view of FIG. 6.

The undisclosed bottom surface of both embodiments is plain and unornamented. The undisclosed side of the second embodiment is identical to those disclosed in the first embodiment.
